UNITED STATES PATENT OFFICE.

WILLIAM R. AMBROSE, OF SHEFFIELD, ALABAMA.

CAR-COUPING.

SPECIFICATION forming part of Letters Patent No. 600,396, dated March 8, 1898.

Application filed July 1, 1897. Serial No. 643,124. (No model.)

To all whom it may concern:

Be it known that I, WILLIAM R. AMBROSE, a citizen of the United States, residing at Sheffield, in the county of Colbert and State 5 of Alabama, have invented new and useful Improvements in Car-Couplings, of which the following is a specification.

This invention relates to that class of car-couplings in which provision is made for supporting a coupling-pin in an elevated position until automatically released by an entering link, with which the coupling-pin then becomes engaged.

It is the purpose of my invention to provide 15 improved means for the automatic coupling of cars and for uncoupling the draw-heads from either the top or sides or car-platform without risk to life or limb.

The invention consists in features of construction and novel combinations of devices in an automatic car-coupling, as hereinafter described and claimed.

In the annexed drawings, illustrating the invention, Figure 1 is a part sectional side elevation of my improved car-coupling, showing a link engaged with the coupling-pin in one draw-head and its other end as entering an opposite draw-head. Fig. 2 is a similar view showing the coupling-pin of one draw-head 25 and its supporting-yoke as being lifted in the act of uncoupling. Fig. 3 is a front elevation of the coupling or draw-head with the pin-supporting yoke in an elevated position. Fig. 4 is a side elevation of a pin-supporting yoke. Fig. 5 is a front elevation of a pin-supporting yoke. Fig. 6 is a perspective of another form 30 of pin-supporting yoke. Fig. 7 is a longitudinal section of a draw-head with link engaged therein. Fig. 8 is a front elevation of draw-head, half in section. Fig. 9 is a top view of draw-head. Fig. 10 is a plan of a double-loop coupling-link.

The draw-head or bumper is designated by the reference-numeral 1 and can be made of 45 malleable or cast iron, soft or hard steel, as preferred. As usual, the draw-head mouth 2 is somewhat beveled, as shown, to facilitate entrance of the coupling-link.

In the top of the draw-head there are provided vertical guideways 3, that may be extended to the under side of the draw-head. These guideways 3 are located on opposite

sides of the upper pin-hole 4 and are designed for passage of a vertically-sliding yoke 5, in which the coupling-pin 6 is carried.

55

The two sides of the yoke 5 are composed of wings 7 at right angles to the longitudinal axis of the draw-head and provided with side bars or pieces 8, that are at right angles to the said wings and parallel with the said draw-head axis. It is preferable to extend the side bars 8 only part way the length of the wings 7 at their lower ends and below the same, as shown in Figs. 1, 2, 5, and 6, but; if desired, the side bars 8 may be extended the whole 60 length of the said wings 7 and also a suitable distance below the same, as shown in Fig. 3. By extending the side bars 8 along only the lower portion of the inwardly-projecting wings 7 the yoke 5 will be considerably lightened 65 70 and its frictional surfaces reduced, so that the vertically-sliding movement of the yoke is facilitated. The inwardly-projecting wings 7 greatly strengthen the yoke and also serve to hold a coupling-link level by bearing on its 75 upper side when the yoke 5 and attached coupling-pin 6 are lowered. At their upper ends the two sides of the sliding yoke 5 may be formed separate to receive between them the upper end of the coupling-pin 6, as shown 80 in Figs. 1 and 3. In this construction of yoke the upper end of the coupling-pin 6 is flattened from front to rear and is pivotally supported between the upper ends of the two separate yoke sides by means of a transverse pin 85 or pivot 9, that also serves to connect the opposite sides of the yoke. The body of the coupling-pin 6 is cylindrical, and it will be obvious that with the form of yoke shown in Figs. 1 and 3 any ordinary coupling-pin can 90 be made serviceable by simply flattening its upper end, so that it can be conveniently pivoted between the upper ends of the two separate side pieces of the yoke.

If desired, the upper portion of the vertically-sliding yoke 5 may be made all in one piece and integral with the side wings, as shown in Figs. 2 and 6. This form of yoke is provided at the top with a collar 10, through which the coupling-pin 6 is inserted and secured by a bolt 11, passed from front to rear. In either form of yoke construction a ring or eye 12 may be provided at the upper end of the coupling-pin 6 as a means for lifting said 95 100

pin and connected yoke in the operation of uncoupling, any suitable chains or operating levers being connected with the said ring or eye.

5 For the purpose of accommodating the angular form of the yoke sides at the junction of the wings 7 and side pieces 8 a similar angular or T-shaped construction is given to the guideways 3 in the upper portion of the

10 draw-head; but this T form of the guideway need not be continued all the way down, as its rear wall may be omitted at the lower part.

To the lower ends of the yoke side pieces 8 it is preferable to attach pivotal fingers by

15 means of any suitably-jointed connection. The jointed connection between the fingers 13 and upper side pieces of the yoke 5 may be by means of a circular boss 14 on one part

20 engaged in a circular opening 15 in the other part. As shown, I prefer to arrange the bosses 14 on the outer sides of the yoke side pieces 8 at their lower ends and to form the open-

25 ings 15 in the upper ends of the pivotal or swinging fingers 13, the connected parts be-

ing recessed to lap by each other and form smooth joints flush on both sides. In this construction the fingers 13 will be attached

when the yoke 5 is inserted downward into and through the top of the draw-head, it be-

30 ing only necessary to slip the bosses 14 of one part into the openings 15 of the other part. No other fastenings will be required, for the

35 guideways 3 will hold the fingers 13 onto the yoke-body. Obviously, however, the yoke

any other suitable form of connecting-joint.

In the lower ends of the yoke-fingers 13 there are openings 16 to receive the ends of a transversely - arranged bolt or axle 17, on

40 which there is loosely or revolvably mounted a metal ball or roller 18, having a doubly-con-

noidal form or tapered toward its ends.

To connect the yoke 5 and ball 18 with the draw-head, the ball or roller will be passed

45 in through the draw-head mouth and the yoke will be let down through the draw-head top.

The ball or roller 18 will then be brought be-

50 tween the lower ends of the yoke or its fingers in proper alinement with the axle-open-

55 ings therein, and the axle 17 will then be in-

serted and engaged with the yoke and ball by passing the said axle in through either one

60 of two openings 19, Fig. 7, provided in oppo-

site sides of the draw-head. It is my purpose

65 to arrange these openings 19 at such a height as to be above the normal limit of vertical movement given to the ball 18 in elevating the yoke, so that the ends of the axle 17 will not come opposite to the said openings 19 ex-

cept as the yoke is intentionally raised to

that extent in order to permit the axle being

pushed out by means of a suitable instru-

ment inserted into one of said openings when

it is desired to disconnect the ball and yoke.

65 As ordinarily the ball-axle will not rise to the

level of the openings 19 the guideways 3 or

side walls of the draw-head will be sufficient

to hold the axle 17 in place without the em-
ployment of any special fastenings. If de-
sired, however, one end of the ball-axle 17 70
may be screwed into the opening 16 of one
yoke-finger, as shown in Fig. 5, and the other
end of the axle may have a head that is coun-
tersunk into the other finger, or the said axle
may be fastened at both ends by heading up 75
or otherwise.

It is the purpose of the ball or roller 18 to
support in an elevated position the vertically-
sliding yoke 5 and the coupling-pin 6 carried

80 by said yoke, the said ball or roller to be ca-
pable of being displaced or pushed backward
by an entering link, so as to release the ele-
vated yoke and permit it to fall, thereby car-
rying the coupling-pin 6 into locking engage-
ment with the link. The rear portion of the 85

draw-head is formed with a recess 20 to re-
ceive the ball or roller 18 when pushed back-
ward in lowering the yoke. The bottom of

90 this recess 20 may be substantially flush with
the bottom of the draw-head, as shown in
Fig. 7, and in this case the ball or roller 18
will be moved forward onto the upper side

of the link as the yoke is elevated in the act
of uncoupling, or, as shown in Figs. 1 and 2,
the recess 20 may be rearwardly depressed, 95

and in this instance the ball or roller 18 will
operate below the link in uncoupling. The

lower ends of the guideways 3 may be con-
tinued in a suitable rearward direction to-
ward or at the sides of the recess 20 or into 100

slots 3^a to accommodate the folding or rear-
ward-swinging movement of the fingers 13 as

the yoke 5 and coupling-pin 6 are lowered.

The rear portion of the draw-head may be
recessed in conformity to the shape and di-
mensions of the ball or roller 18, or the draw-
head recess may be of any shape and capac-
ity. The size of the ball or roller 18 may be
varied as desired.

When a link is entered into a draw-head 110
having its yoke 5 elevated, the impact of the
link against the ball or roller 18 will push the
latter rearward, thereby releasing the yoke

and permitting it to fall. The coupling-pin 6
thus passes into engagement with the link, 115

and the lower ends of the yoke-wings 7 will
rest on the side bars of the link and hold it

level. It is thus unnecessary to provide the
coupling-pin with a shoulder to bear on the

link. Besides serving to hold the link level 120
the inwardly-projecting wings 7 are impor-
tant as strengthening the yoke.

It is preferable to bevel the mouth 2 of the
draw-head at its top, bottom, and sides in

order to direct an entering link toward the 125
ball or roller 18, so that there will be a proper
impact to dislodge the ball from beneath the

elevated yoke 5 and insure a ready and easy

coupling.

In some instances the link attached to one 130
draw-head may have an upward tilt toward
the other that would tend to carry the link
above the ball or roller 18, and to prevent
this there may be provided in the upper por-

- tion of the draw-head mouth a forwardly-swinging lug 21, supported by a pivot-pin 22 at the top. This pivotal forwardly-swinging lug or dog 21 is so supported in a recessed portion of the draw-head top as to be incapable of swinging rearward, but is free to swing forward, so as not to obstruct withdrawal of a link from the draw-head. The front face of the forwardly-swinging dog 21 is beveled downward and rearward to direct an entering link toward the ball or roller 18, thus facilitating dislodgment of the said ball or roller in the act of coupling two cars together. In the operation of uncoupling if the link should be lifted sufficiently to catch against the rear side of the pivoted forwardly-swinging dog 21 there will be no obstruction to withdrawal of the link, for the pivoted dog will readily yield in a forward direction.
- 20 The front upper portion of the dog 21 is set in flush with the draw-head face, so that it is not subjected to the shock of impact when two draw-heads come together.

When the cars are coupled, the pin 6 firmly engages in a pin-opening 23 in the bottom of the draw-head as well as in the upper pin-hole 4, through which it is suspended at the top, and thus the vertically-sliding yoke 5 is entirely relieved from strain. Should the 30 coupling-pin break, it may be readily replaced by any of the cylindrical coupling-pins in common use.

By lowering the yoke 5 and attached coupling-pin 6, with the ball or roller 18 pushed back into the draw-head recess 20, the pin 6, extending across the inner portion of the draw-head mouth, will serve as a guard to prevent accidental coupling, as where cars are standing in a railroad-yard or on a siding.

40 The coupling-pin 6 can be made cylindrical, as shown, or it may be elliptical in cross-section from front to rear or constructed in any other form desired; but obviously the cylindrical form is preferable as being more easily replaced by such pins as are in common use. At its lower end the pin 6 may be squared off flat, or it may be beveled or convexed, as may be preferred.

A coupling-link 24 of the double-loop form shown in Fig. 10 may be used with this coupler for automatic coupling with knuckle-couplers, one loop of the said link 24 being put onto the knuckle-coupler and the other loop being coupled by impact with the ball-supported yoke and coupling-pin hereinbefore described; but any ordinary link, as 25, may be also used with this coupling.

What I claim as my invention is—

1. In a car-coupling, the combination of a recessed draw-head having upper and lower pin-holes and provided with guideways in the draw-head top at the sides of the upper pin-hole, a vertically-sliding yoke engaged in said guideways, a coupling-pin carried by the upper portion of said yoke, and a ball or roller revolvably mounted in and between the lower portions of said vertically-sliding yoke, to

support the yoke and coupling-pin in an elevated position and adapted to be displaced by impact of an entering link, whereby the 70 yoke is caused to drop and carry the coupling-pin into engagement with the link and with the lower ends of the yoke-wings bearing on the link, substantially as described.

2. In a car-coupling, the combination of a recessed draw-head provided with upper and lower pin-holes and having guideways in the draw-head top at the sides of the upper pin-hole, a vertically-sliding yoke fitted into said guideways and provided with inwardly-projecting wings and with side pieces attached to said wings at a right angle and projecting below the same, a coupling-pin carried by the upper portion of said yoke, and a ball or roller revolvably mounted in and between the lower 80 portions of said vertically-sliding yoke, to support the yoke and coupling-pin in an elevated position and adapted to be displaced by impact of an entering link, whereby the yoke is caused to drop and carry the coupling-pin into engagement with the link, 90 substantially as described.

3. In a car-coupling, the combination of a recessed draw-head provided with upper and lower pin-holes and having angular guideways in the draw-head top at the sides of the upper pin-hole, a vertically-sliding yoke composed of two separate side pieces provided with inwardly-projecting wings and fitted into said guideways, a coupling-pin carried 100 by and between the upper portions of the two sides of said yoke, and a ball or roller revolvably mounted in and between the lower portion of said vertically-sliding yoke, to support the yoke and coupling-pin in an elevated 105 position and adapted to be displaced by impact of an entering link so that the yoke will be caused to drop and carry the coupling-pin through the link and the lower ends of the yoke-wings onto the side bars of the link, 110 substantially as described.

4. In a car-coupling, the combination of a recessed draw-head provided with upper and lower pin-holes and having guideways in the draw-head top at the sides of the upper pin-hole, a vertically-sliding yoke fitted into said guideways and provided with inwardly-projecting wings, a coupling-pin carried by the upper portion of said yoke, swinging fingers pivotally attached to the lower portions of the 115 said yoke, and a ball or roller revolvably mounted in and between the lower ends of said fingers to support the said yoke and coupling-pin in an elevated position and adapted to be displaced by an entering link to cause the 120 yoke to drop and carry the coupling-pin into engagement with the link, substantially as described.

5. In a car-coupling, the combination of a recessed draw-head provided with upper and lower pin-holes and with guideways in the draw-head top at the sides of the upper pin-hole, a vertically-sliding yoke fitted into said guideways, a coupling-pin carried by the up-

per portion of the vertically-sliding yoke, swinging fingers pivotally attached to the lower portions of the yoke, and a doubly-conoidal roller revolvably mounted in and between said swinging fingers and provided with a removable axle adapted to be inserted and removed through openings in the sides of the draw-head, substantially as described.

In testimony whereof I have hereunto set my hand in presence of two subscribing witnesses.
